Lacy & Harry, Attorneys

UNITED STATES PATENT OFFICE.

JOHN MAPES, OF FORT MADISON, IOWA.

CAR DOOR.

Application filed October 4, 1924. Serial No. 741,631.

To all whom it may concern:

Be it known that I, JOHN MAPES, a citizen of the United States, residing at Fort Madison, in the county of Lee and State 5 of Iowa, have invented certain new and useful Improvements in Car Doors, of which the following is a specification.

The object of this invention is to provide means whereby a freight car door may be 10 easily moved from closed to open position or from open to closed position and securely held in the closed position to prevent unauthorized access to the interior of the car. The invention consists in certain novel features which will be hereinafter first fully described and then more particularly pointed out in the appended claims.

In the accompanying drawing:

Figure 1 is a side elevation of a portion 20 of a freight car having my improved door fitted thereto;

Fig. 2 is a vertical section on the line 2—2 of Fig. 1;

Fig. 3 is a horizontal section on the line 25 3—3 of Fig. 1;

Fig. 4 is a detail perspective view of one of the upper slidable bearings, and

Fig. 5 is a similar view of one of the lower bearings.

The car, indicated at 1, may be of any preferred construction and dimensions and is provided with a door opening 2 in its side. The door 3 is rabbeted or countersunk, as indicated at 4, and of proper dimensions to 35 fit closely within the door opening and is mounted for travel upon an upper track 5 which is secured on the outer side of the car horizontally of the same and extends over the door opening, as clearly shown in 40 Fig. 1.

Adjacent the side edges of the door at the upper and lower ends thereof, I secure upon the outer side thereof bearing brackets 6 in which are journaled vertically disposed 45 rock shafts 7 which are provided intermediate their ends with cranks 8 connected by a link 9 so that simultaneous movement of the rock shafts will be effected. The ends 50 of the rock shafts are offset or formed into cranks, as shown at 10, and the terminals of the shafts are rotatably fitted in shoes 11 and 12, respectively.

As shown clearly in Fig. 1, the upper track rail 5 is substantially T-shape in cross section, being formed with vertical flanges 13 and 14 on its upper and lower sides, and

the shoes 11 are provided with lips 15 and 16 which are adapted to engage behind the respective flanges with the body of the respective shoe bearing against the front or 60 outer side of the rail, so that the shoes will provide firm bearings for the upper terminals of the rock shafts but may slide easily upon the rail as the door is opened or closed. The lower shoes, 12, are forked, as at 17, 65 in their under sides to span a bar 18 which connects the lower ends of posts 19 and is secured thereto in any convenient manner. The posts 19 and bar 18 thus form in effect 70 a frame which surrounds the sides and bottom of the door, as shown. The shoes 12 are fixed upon the bar 18. A track rail 20 is secured to the side of the car below the door opening, and rollers 21 are carried by the posts 19 or the bar 18 to run upon said 75 track, the lower ends of the posts being offset, as at 22, 23, to clear the side of the car.

The posts 19 extend upwardly beside the edges of the door to the full height of the 80 door, and are provided, adjacent their upper extremities, with bearing openings, 24, receiving pintle pins 25 which are secured upon the outer side of the door at the upper end thereof, the weight of the door being 85 thus transferred to and carried by the posts. One of the rock shafts 7 is provided near its lower end with a crank or lever handle member 26 which may be readily grasped from the ground and to the free end of this 90 member is pivoted a latch 27 adapted to engage over an eye or loop 32 on the car door which loop or eye is adapted to receive a lock or seal at the outside of the handle whereby unauthorized opening of 95 the door will be prevented. When the latch 27 is thus secured, as shown in Fig. 1, the rock shafts 7 can not be turned and the door will be secured in the closed position.

A weather strip 33 is secured on the car 100 above the door opening to shed rain and like elements so that moisture may not leak into a loaded car through the door opening.

It is thought the operation will be readily understood. When the door is closed, it 105 fits closely within the door opening, as shown most clearly in Figs. 2 and 3, and the handle member is engaged over the loop or eye and sealed or locked thereto. In this position, the cranks 10 of the rock 110 shafts 7 will extend inwardly from the terminals of the rock shafts so that the door

will be held in its closed position fitting snugly in the door opening. When the door is to be opened, the lock is removed and the handle member 26 swung outwardly, thereby causing the rock shafts to rotate about their terminals and cause the cranks 10 to project outwardly. Inasmuch as the shafts 7 above and below the respective cranks extend through bearings 6 upon the car door, the door will be caused to swing outwardly to clear the door opening and assume a position outwardly beyond the car body after which the door may be moved readily along the tracks 5 and 20 beyond the door opening to the position shown in dotted lines in Fig. 1. When the door moves outwardly, the posts 19 and the bar 18 rock on the lower track so that their upper ends swing outwardly but the door moves pivotally at the pintles 25 so that it remains perpendicular. Of course, a reverse operation of the parts will bring the door again into the door opening to close the car.

My device is exceedingly simple in the construction and arrangement of its parts and may be easily operated. The door will move easily and quickly from one position to another and the construction is such that an accumulation of snow or ice is not apt to occur.

Having thus described the invention, I claim:

1. The combination of a car having a door opening, of tracks secured upon the car above and below said door opening, the upper track being T-shaped in cross section whereby to provide upper and lower vertical flanges, a door, shoes at the top of the door constructed to slidably engage the flanges of the track, shoes at the bottom of the door, rock shafts having their terminals journaled in said shoes and being bent to form cranks adjacent said terminals, the intermediate portions of the rock shafts being journaled upon the outer side of the door, said rock shafts having arms and a rod connecting said arms and being journaled thereon whereby simultaneous turning of said shafts is effected and which turning will swing the door in horizontal plane into

and out of said door opening, posts at the sides of the door, a bar connecting the lower ends of the posts, the lower shoes being secured to said bar, rollers at lower ends of the posts mounted to travel on the lower track, and pintles secured to the outer side of the door at the top of the same and pivotally engaged in the posts.

2. The combination with a car having a door opening, of tracks secured to the car above and below said door opening, a door, a frame surrounding the sides and bottom of the door and resting on the lower track, shoes at the top of the door slidably engaging the upper track, shoes secured to the bottom of the frame, rock shafts journaled on the outer side of the door and having their ends provided with cranks and their terminal portions journaled in said shoes, a connection between the rock shafts whereby simultaneous turning of said shafts is effected and which turning will swing the door in a horizontal plane into and out of said opening, and a pivotal connection between the upper portion of the door and the upper portion of said frame.

3. The combination with a car having a door opening, of tracks secured upon the car above and below said door opening, a door, shoes at the top of the door slidably engaging the track, shoes at the bottom of the door, rock shafts having their terminals journaled in said shoes and being bent to form cranks adjacent said terminals, the intermediate portions of the rock shafts being journaled upon the outer face of the door, said rock shafts having arms and a rod pivotally connecting said arms whereby simultaneous turning of said shafts is effected and which turning will swing the door in a horizontal plane into and out of said door opening, posts at the sides of the door, a bar connecting the lower ends of the post, the lower shoes being secured to said bar, rollers at the lower ends of the posts mounted to travel on the lower track, and pintles secured to the door at the top of the same and pivotally engaged in the posts.

In testimony whereof I affix my signature.
JOHN MAPES. [L.S.]
